UNITED STATES PATENT OFFICE

BERNARD S. PURINTON, OF EAST LIVERPOOL, OHIO

PROCESS AND APPARATUS FOR CASTING CERAMIC ARTICLES

Application filed July 27, 1931. Serial No. 553,286.

The present invention relates to the casting of ceramic articles, and more especially to the casting of ceramic articles such as chinaware, porcelain and semi-porcelain 5 tableware, in water absorbent molds.

In the ceramic industry tableware articles, such as pitchers, covered dishes, casseroles, and like shapes, which cannot be made on a jigger, are usually made by casting in water 10 absorbent plaster of Paris molds. A fluid slip of ceramic material is poured by the workmen into the mold and allowed to stand therein until the workman judges that sufficient time has elapsed for a semi-solid coherent layer of the ceramic material to have 15 become deposited against the walls of the mold due to the absorption of the water from the slip. The workman then pours out the excess slip. The mold and its contained semi-solid layer of ceramic material therein is allowed to dry. The mold is then opened and the article, such as the pitcher or dish, is removed and finished by applying the glaze and 20 firing.

This process as carried out in the manufacturing plant is a hand operation, the molds being filled and emptied by workmen. The thickness of the walls of the article is determined by the judgment of the workman 25 in emptying the excess slip after he believes that sufficient time has elapsed for a layer of proper thickness to become deposited in the mold.

The labor cost of making articles by this 30 casting method is so high that it has been limited to the making of those articles such as casseroles, covered dishes, pitchers, etc., which cannot be made on a rotary table or jigger. Cups, plates, and the like, are usually 35 made on a rotary table or jigger from a bat of plastic ceramic material. The jiggering process is cheaper than the casting process and is therefore used when possible, although the jiggered product is inferior due to air 40 blisters, strains, etc.

The object of my invention is to cheapen 45 the cost of production by the casting process, whereby it can be employed not only in making articles such as pitchers, covered dishes, and the like, but also for making cups,

plates, etc., which have heretofore been generally made on a jigger.

In carrying out my process, a water absorbent mold, such as a plaster of Paris mold, is immersed in a bath of fluid ceramic slip 55 which rises into and fills the mold. The mold is allowed to remain in the slip bath for a predetermined time and is then removed, allowing the excess slip to drain from the mold. This process readily adapts itself for machine operation, whereby the operations of dipping and removing the molds from the slip can be carried out by machinery, thus doing away with manual labor and predetermined the time of immersion and thereby 60 accurately controlling the thickness of the layer deposited in the molds.

In the drawings, there is illustrated diagrammatically apparatus for carrying out my process.

In the illustrated embodiment of my invention,

Figure 1 is a bottom plan view of a set of plaster of Paris cup molds;

Figure 2 is a section along the line II-II 75 of Figure 1;

Figure 3 is a vertical section through the molds along the line II-II of Figure 1 illustrating the molds as immersed in the tank or slip;

Figure 4 illustrates a modification, being an interior view of half of a plate mold; and

Figure 5 is a vertical section through a plate mold immersed in a bath of slip.

Referring to the illustrated embodiment 85 of the invention illustrated in Figures 1, 2 and 3, a number of cup molds 1 are formed in a slab or body 2 of water absorbent material, such as plaster of Paris. The mold is used in an inverted position, as shown in the drawings. The tops of the mold cavities 1 have vent holes 3 which allow the escape of entrapped air when the molds are immersed in the slip bath. In Figure 3 the molds are 90 shown as dipped into a bath 4 of the usual ceramic slip held in a tank 5. The set of molds is dipped, preferably by machinery, into the bath 4 of slip. As illustrated in Figure 3, the molds are shown as resting on a 95 100

grid 6 which allows the slip to enter the mold cavities 1.

The slip 4 is the usual fluid slip, such as is used in the hand plaster of Paris mold casting operation. It is formed by a water suspension of a mixture of clay, feldspar and flint, together with small amounts of soda ash and silicate of soda to help hold the clay mix in suspension. The slip is prepared in the usual way in a blunger and is poured into the tank 5.

When the molds 1 are dipped into the bath of slip, the slip rises and fills the mold cavities, as shown in Figure 3. The entrapped air escapes through the vents 3.

The plaster of Paris mold body, because of its water absorbent properties, absorbs the water from the slip adjacent the mold surfaces, and causes a semi-solid coherent layer of the ceramic material to collect against the inner faces of the molds, as indicated at 7 in Figure 3. The molds are allowed to remain in the bath of slip until this semi-solid coherent layer of ceramic material is formed to the desired thickness for the walls of the article being cast. Then the molds are removed from the tank, preferably by machinery. In removing the molds, they are usually tilted slightly to allow the air to enter at one side of the bottom mold cavity openings and the excess slip to run out and back into the bath. The molds with their deposited layers of ceramic mix are then dried, preferably in a drying room. The drying causes a slight shrinkage of the ceramic material, which permits the articles, such as the cups in the illustrated embodiment, to be readily removed from the molds preparatory to being finished by glazing and firing. The sprues 8 formed by the material which may enter the vent openings 3 are readily cut off of the articles.

Since the height to which the slip may rise in the vent openings 3 is controlled by the depth to which the molds are dipped in the bath, there is no wasting or escaping of the slip through the vent holes, as would be the case in a pressure casting operation.

As illustrated in Figures 1, 2 and 3 of the drawings, the surfaces of the mold cavities 1 and the top surface of the plaster of Paris slip 2 are formed from the surface of the plaster of Paris, so that the mold cavities may absorb water and so that the water can be readily dried therefrom at the top surface of the mold body as well as from the mold surfaces. The bottom surface of the mold body and the side surfaces are preferably coated or glazed with a waterproof layer 9 to prevent the deposit of the material at the places where this is not wished.

This process adapts itself readily to machine operation. The molds can be dipped into the tank of slip by machinery and held therein for a predetermined time and then

automatically removed, thus not only doing away with manual labor, but also substituting mechanically timed operations for the judgment of the operator which is now relied upon in the manual process. The relatively large body of slip in the tank can be accurately controlled and maintained as to conditions of fluidity, etc.

In Figures 4 and 5 there is illustrated a modification, which consists of a mold for casting a solid article, such as a plate, as distinguished from hollow articles, such as cups which are illustrated in Figures 1, 2 and 3.

The mold is a split mold consisting of two halves 10 and 11 which are formed of plaster of Paris. The mold cavity 12 having the shape of a plate, is formed between the two halves of the split mold. A bottom feeder opening 13 and side feeder openings 14 are provided for admission of the fluid slip into the mold when it is dipped into the slip bath. An air vent opening 15 is provided to allow the escape of air trapped in the mold when it is immersed. The outer surfaces of the mold are preferably coated or glazed with a waterproof layer 16, which prevents the deposit of the slip material at places where this is not wished. As shown in Figure 5, the mold is immersed in a bath 17 of fluid slip which by its natural hydraulic pressure feeds itself through the feed openings 13 and 14 to supply the ceramic material which solidifies into a semi-solid coherent mass within the mold cavity due to the absorption of the water from the slip by the water absorbent plaster of Paris. After this coherent semi-fluid body of ceramic material is formed from the slip within the mold, the mold is removed from the bath and opened, and the body of the plate 18 is allowed to dry and is then removed from the mold preparatory to finishing by glazing and firing.

While I have illustrated and described the preferred apparatus and process for carrying out my invention, it is to be understood that the invention is not so limited but may be otherwise embodied and practiced within the scope of the following claims.

I claim:

1. The process of casting ceramic articles, which comprises dipping into a bath of fluid ceramic slip a water absorbent mold which is open at its bottom, venting the air trapped in the mold and causing the slip to rise into and fill the mold cavity and remain therein until a semi-solid coherent layer of ceramic material is deposited against the absorbent mold surfaces, and then removing the mold from the bath.

2. The process of casting ceramic articles, which comprises dipping into a bath of fluid ceramic slip a water absorbent mold which is open at its bottom, venting the air trapped in the mold and causing the slip to rise into

and fill the mold cavity and remain therein until a semi-solid coherent layer of ceramic material is deposited against the absorbent mold surfaces, raising the mold from the bath, and allowing the excess slip to drain therefrom.

3. The process of casting ceramic articles, which comprises dipping into a bath of fluid ceramic slip a water absorbent mold which is open at its bottom, venting the air trapped in the mold and causing the slip to rise into and fill the mold cavity and remain therein until a semi-solid coherent layer of ceramic material is deposited against the absorbent mold surfaces, raising the mold from the bath and allowing the excess slip to drain therefrom, drying the material deposited in the mold, and removing it therefrom.

4. Apparatus for casting ceramic articles, comprising a tank holding a fluid bath of ceramic slip, and a water absorbent mold adapted to be dipped into the bath having a mold cavity open at the bottom to allow the ceramic slip to rise into the mold when immersed.

5. Apparatus for casting ceramic articles, comprising a tank holding a fluid bath of ceramic slip, and a water absorbent mold adapted to be dipped into the bath having a mold cavity open at the bottom to allow the ceramic slip to rise into the mold when immersed and a vent at the top of the cavity to allow the escape of entrapped air.

In testimony whereof I have hereunto set my hand.

BERNARD S. PURINTON.
